CLAIM

The ornamental design for an auxiliary step platform for ladder, as shown and described.

DESCRIPTION

FIG. 1 is a front perspective view of an auxiliary step platform for ladder, in accordance with an embodiment; FIG. 2 is a top view of the auxiliary step platform for ladder of FIG. 1;

FIG. 3 is a bottom view of the auxiliary step platform for ladder of FIG. 1;

FIG. 4 is a front view of the auxiliary step platform for ladder of FIG. 1;

FIG. 5 is a rear view of the auxiliary step platform for ladder of FIG. 1;

FIG. 6 is a side view of the auxiliary step platform for ladder of FIG. 1;

FIG. 7 is a top perspective view of the auxiliary step platform for ladder of FIG. 1; and,

FIG. 8 is a bottom perspective view of the auxiliary step platform for ladder of FIG. 1.

The broken lines in FIGS. 1, 2 and 4-7 are included only for the purpose of illustrating portions of the article and forms no part of the claimed design.

1 Claim, 8 Drawing Sheets
